UNITED STATES PATENT OFFICE.

CORNELIUS L. TAYLOR, OF HUNTINGTON, WEST VIRGINIA.

HEATING STOVE.

Application filed July 30, 1921, Serial No. 488,645. Renewed April 4, 1923.

To all whom it may concern:

Be it known that I, CORNELIUS L. TAYLOR, a citizen of the United States, residing at Huntington, in the county of Cabell and 5 State of West Virginia, have invented certain new and useful Improvements in Heating Stoves, of which the following is a specification.

This invention relates to improvements in 10 heating stoves and more particularly that type designed for the consumption of gaseous or liquid fuel, the primary object of the present invention being to provide a stove which will be economical in its consumption 15 of fuel and will possess maximum efficiency as a heat radiating medium.

Another object of the invention is to so construct a stove of the type above mentioned as to insure of perfect combustion of 20 all of the fuel delivered from the burners, thereby obviating the annoyance of incompletely consumed products of combustion escaping from the stove.

Another object of the invention is to so 25 construct the stove that while it will possess maximum efficiency as a heating medium, it may be of compact form and will therefore occupy but little space.

In the accompanying drawings:

30 Figure 1 is a perspective view of the heating stove embodying the invention;

Figure 2 is a vertical longitudinal sectional view through the stove;

35 Figure 3 is a vertical transverse sectional view taken substantially on the line 3—3 of Figure 2 looking in the direction indicated by the arrows;

Figure 4 is a perspective view of one of the baffles of the stove removed.

40 The body of the stove may be constructed in various ways and the component parts thereof may be cast or may be formed from sheet metal as found desirable. The said body comprises side walls 1, end walls 2, a bottom 3, and a top 4. Preferably the walls 1 and 2 and the bottom 3 and the top 4 are lined with sheet asbestos as indicated by the numeral 5, and the top 4 is provided with a dome 6 upstanding from its central portion and having its walls formed with openings 7 for the escape of heated air currents and consumed products of combustion.

55 The body of the stove may be supported in any suitable manner as for example upon corner legs 8 and in order that air may be admitted to the interior of the stove to sup-

port combustion at the burners, the side walls 1 of the body are formed, immediately above the bottom 3, with openings 9.

The burner of the stove is indicated in 60 general by the numeral 10 and may be constructed for the consumption of either gaseous or liquid fuel, the burner in the embodiment of the invention shown in the drawings, comprising a burner tube 11 provided 65 with a longitudinal series of upwardly presented tips 12, the whole being surmounted by a flame spreader indicated by the numeral 13. The burner tube 11 in the illustrated embodiment extends longitudinally 70 medially of the bottom 3 as best shown in Figures 2 and 3 of the drawings.

In order that the passage of the heated air currents and products of combustion through the stove may be retarded so as to 75 increase the efficiency of the stove as a heating medium, there is provided within the stove body an arrangement of baffles which will now be described. One of the baffles is clearly shown in Figure 4 of the drawings 80 and indicated by the numeral 14 and the same comprises an oblong rectangular slab 15 of fire clay or other refractory material, the slab being of dimensions to fit more or less exactly within the body of the stove in 85 a horizontal position as shown in Figures 2 and 3. The slab 15 is provided at one end with a recess 16, and the slabs are arranged and supported within the stove body by being disposed at their ends upon supporting ledges 17 preferably in the nature of angle bars secured upon the inner sides of the end walls 2 of the stove body. The slabs are supported by the ledges 17 in 90 spaced relation one above another and they 95 are so arranged that the recesses 16 will be located alternately at opposite ends of the stove body throughout the series of slabs as shown in Figure 2, these recesses constituting passage ways for the heated air currents 100 and products of combustion. By reference to Figure 2 it will be understood that the heated air currents and products of combustion and also the flames from the burner will impinge against the under side of the 105 lowermost slab 15, passing up through the passage way at the end of this slab and thence longitudinally within the stove body in the space between the said slab and the one next above it, from which space the 110 products of combustion and heated air currents will pass through the passage way of

the last mentioned slab, and so on throughout the entire series of slabs, being finally discharged through the openings 7 in the dome 6. Thus the heated air currents and products of combustion are retarded in their passage upwardly through the interior of the body of the stove and perfect combustion of the fuel is insured.

Having thus described the invention what is claimed as new is:

In a heating stove of the class described, a body having side walls, end walls, and a bottom, a burner arranged longitudinally on the bottom, a narrow apertured flame spreader secured to the burner and extending longitudinally thereof, said body being

provided with air intake openings located adjacent the bottom, a dome on the top of the body having openings through its sides, supporting ledges upon the end walls of the body, and flat baffle slabs resting horizontally upon said ledges and having their edges abutting the respective walls of the body, said slabs being each provided with a recess in one end and the slabs being arranged in spaced relation one above the other with said recesses alternately at opposite ends of the body, said flame spreader being situated between said burner and the lowermost one of said slabs.

In testimony whereof I affix my signature.
CORNELIUS L. TAYLOR. [L.S.]
